UNITED STATES PATENT OFFICE.

UBALD HEBERT, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

SHUTTLE.

1,226,613.

Specification of Letters Patent.

Patented May 15, 1917.

Application filed February 5, 1916. Serial No. 76,270.

To all whom it may concern:

Be it known that I, UBALD HEBERT, a citizen of the United States, residing at Manchester, in the county of Hillsboro and State of New Hampshire, have invented an Improvement in Shuttles, of which the following description, in connection with the accompanying drawings, is a specification, like letters on the drawings representing like parts.

10 The invention to be hereinafter described relates to shuttles, and more particularly to shuttles employed in looms for weaving.

The ordinary loom shuttle used in what 15 is generally known as the common loom is provided with a skewer or spindle hinged at one end to the shuttle body, and when a filling carrier or bobbin supplied with filling is to be placed in the shuttle, the skewer or 20 spindle is swung upon its pivotal connection with the shuttle-body to carry the free end of the skewer or spindle outside the shuttle. The filling carrier or bobbin is then placed upon the skewer or spindle and the latter is 25 swung into the shuttle again or back to initial position. Such shuttles are provided at one end with a thread eye through which the end of the filling or yarn in the shuttle is threaded by the loom operative or by hand.

30 Filling replenishing looms are of two general types, those that effect replenishment by changing the filling carrier or bobbin in the shuttle, and those that change the shuttle itself. In either case, however, it is desirable in weaving some grades of fabrics 35 to effect replenishment of filling when that in the active shuttle reaches substantial exhaustion. One means familiar to those skilled in the art for bringing about such

40 replenishment consists of a feeler motion having a part that feels for the filling in the shuttle on the detecting beat of the lay, and when it finds the filling to be substantially exhausted sets a train of mechanism in condition for replenishing the filling. In its 45 feeling action the said part may enter a slot or opening in the filling carrier or bobbin when the filling is substantially exhausted, and be not moved on the detecting beat of the lay. When such form of feeler is 50 employed, the filling carrier or bobbin must be positioned in the shuttle so that the open-

ing or slot in the carrier or bobbin shall be presented opposite the feeler on the detecting beat, and since the feeling part of the 55 feeler enters the slot or opening in the carrier or bobbin, it is desirable that its proper action shall not be impaired by the presence of the skewer or spindle employed to hold the carrier or bobbin in the shuttle. On the 60 other hand, however, when replenishment is effected by changing shuttles, it is important that the means for holding the filling carriers or bobbins in the shuttles shall be such as to permit the operative to readily 65 remove the old or depleted carrier or bobbin by hand, and replace it by one having a working supply of filling.

An important feature of the present invention, therefore, consists in a shuttle 70 wherein the carrier or bobbin-holding means comprises jaws for engaging the exterior of the carrier or bobbin and a fixed fulcrum point on the shuttle for engagement by the carrier or bobbin as it is turned into operative 75 relation with said jaws.

Another important feature of the invention consists in a shuttle having bobbin-holding jaws and a fulcrum point between the planes passing longitudinally of said 80 jaws about which the bobbin is turned as it is moved into operative relation with said jaws.

A still further feature of the invention consists in guiding means for guiding the bobbin 85 as it is turned about its fulcrum into operative relation with the bobbin-holding jaws.

The above and other features of the invention will be described hereinafter and then will be made the subject of claims. 90

In the drawings:

Figure 1 is a plan view of a loom shuttle, parts being broken away, showing one form of the present invention;

Fig. 2 is a longitudinal section on the 95 lines 2-2, Fig. 1;

Fig. 3 is a sectional view similar to that of Fig. 2 with certain parts in elevation, showing the first position of a filling carrier or bobbin as it is being placed in the 100 shuttle by hand;

Fig. 4 is a view similar to that of Fig. 3, but showing the filling carrier or bobbin turned into operative position in the shuttle;

Fig. 5 is a side elevation of a portion of the filling carrier or bobbin detached; and

Fig. 6 is an end view looking at the base or head portion of the bobbin.

5 The shuttle body 1 is shown as of the common type having a cavity 2 for the reception of the filling carrier or bobbin and its wound mass of filling, and provided with a thread eye. In the present instance, the 10 thread eye is shown as of the closed type comprising a tubular portion 3 leading into a side delivery portion 4*, but the thread eye may be of any usual character whereby the filling leading from the carrier or bobbin 15 may be placed therein for delivery as the shuttle travels across the lay.

Shuttles of the type used in common plain looms have a skewer or spindle pivotally mounted therein for receiving and holding 20 the carrier or bobbin and its load, but this invention contemplates that such skewer or spindle shall be omitted and means be provided which shall enable the bobbin to be readily turned by hand about a fixed point into 25 or out of holding engagement with the bobbin-holding jaws, as will now be described.

The end of the shuttle remote from the delivery eye is provided with bobbin-holding jaws adapted to engage projections or rings 30 upon the base or head of the bobbin. It would be difficult ordinarily, to insert a bobbin between the holding jaws, because these jaws must be made sufficiently stiff to hold the bobbin firmly when in position between 35 them; and difficulty would also be experienced in removing a bobbin from between said jaws, because in the absence of means to prevent it, the bobbin if swung outwardly, would turn about an axis extending from 40 one jaw to the other and still be clamped between the jaws. The present invention, therefore, contemplates a fulcrum point or lug carried by the shuttle in such position that when the bobbin head is engaged by 45 the fulcrum or lug, the bobbin may be turned about such fulcrum into or from engagement with the embracing jaws.

The bobbin-holding jaws may be variously contrived and secured to the shuttle body, 50 and likewise the fixed fulcrum point or lug to be engaged by the base of the bobbin may be variously formed, and related, to the holding jaws. In the present instance, the shuttle is recessed at 4 and the bobbin-holding 55 jaws 5 extend from a part 6 held in said recess by suitable means, such as the screw 7.

The part 6 may be formed as a block from which the jaws 5 curve, as at 8, to the bobbin-holding portions which may be provided with the usual recesses 9 adapted to engage suitable projections or rings 10 secured to or forming part of the bobbin head or base, as indicated in Figs. 3, 4 and 5. The fulcrum or lug to be engaged by the

bobbin and about which the bobbin is turned as it is swung into or out of engagement with the bobbin-holding jaws, is connected to the shuttle-body between the jaws or between planes passing longitudinally of the jaws. In the present instance of the 70 invention, the fulcrum is formed as a lug 11 projecting from the metal strip 12 which may be extended toward the end of the shuttle, as in Figs. 2, 3 and 4 and secured in place by suitable means, such as the screw 75 13. The strip 12 in this instance of the invention has an inclined portion 14 between the jaws from which the fulcrum lug 11 extends, and its lower portion 15 is turned frontward or toward the end of the shuttle 80 to underlie the block 6.

The base portion of the bobbin as indicated in Fig. 6 is provided with an opening 16 adapted when the bobbin is placed in position as in Fig. 3, to engage the fulcrum 85 or lug 11, and in order that the bobbin may be turned downward from the position of Fig. 3 about the fulcrum 11 as a center without binding thereon, the fulcrum is preferably formed conical in shape as indicated 90 in Figs. 1 and 2. This conical formation of the fulcrum point is preferred, but it is obvious that its contour may be variously formed, the essential in this respect being that it shall be adapted for engagement with the recessed head portion of the bobbin as indicated in Fig. 3 to enable the bobbin to be turned downward about said fulcrum for bringing the projections or rings 10 on the bobbin into holding engagement with the holding grooves 9 in the bobbin-holding 100 jaws.

Extending from the upper portion of the bobbin-holding grooves 9 in the jaws 5 are the incline grooves 17 which, when the bobbin is in position as indicated in Fig. 3, are adapted to initially engage the projections or rings 10 on the bobbin, the construction being such that as the bobbin is turned downward from position as indicated in Fig. 3 into holding relation with the bobbin-holding jaws as indicated in Fig. 4, the incline groove portions 17 engaging the projections or rings 10 restrain the bobbin from longitudinal movement, and direct it downwardly about the fulcrum 11 as a center into holding relation with the bobbin-holding jaws. These incline grooves 17, as indicated 115 in Fig. 3, extend from the top portion of the bobbin-holding groove 9 in a direction upwardly and toward the bobbin-holding end of the shuttle.

From the construction thus far described, it will be seen that the shuttle is not provided with a skewer or spindle and that when a bobbin is to be placed in the shuttle, the recessed portion 16 thereof is first engaged upon the fulcrum or lug 11 at which

time the projections or rings 10 on the bobbin head or base are in position for engagement with the upwardly and outwardly inclined grooves 17 of the bobbin-holding jaws, and upon the application of downward pressure to the free end of the bobbin, the projections or rings 10 on the bobbin head are guided downwardly by the grooves 17 into bobbin-holding relation with the 10 grooves 9 of the bobbin-holding jaws until the parts have assumed position as indicated in Fig. 4, at which time the bobbin is firmly held between the bobbin-holding jaws. Likewise, in removing a bobbin from the 15 shuttle, the parts being in position as indicated in Fig. 4, the free end portion of the bobbin is seized by the hand of the operative and turned upwardly, whereupon the recessed portion 16 at the base of the bobbin 20 again turns about the projection 11 as a fulcrum, with the result that the projections or rings 10 are readily turned upwardly, out of engagement with the bobbin holding jaws, and the bobbin can be taken directly 25 from the shuttle.

In a filling replenishing loom of the type wherein a feeler mechanism is employed to feel for the filling in the shuttle on the detecting beat of the lay and, when the filling 30 has become substantially exhausted, enters a recess or slot 21 in the bobbin, it is necessary that the slot or recess 21 in the bobbin shall be positioned for the entrance of the feeler. To this end, the bobbin and shuttle 35 are provided with interengaging guiding members which shall determine the rotative position of the bobbin as it moves to its operative position in the shuttle as indicated in Fig. 4. These interengaging members may 40 be variously formed, and in the present instance the bobbin is provided with a portion 18, Figs. 5 and 6, having the slabbed-off portions 19 at the sides which are adapted to engage guides 20 secured to the shuttle so 45 that as the bobbin is turned downwardly from the position of Fig. 3 to that of Fig. 4, the portions 19 of the bobbin may engage the guides 20 and be held from rotative movement.

50 The guides 20 have at their upper portions outwardly-flaring guide wings 22 which, when the bobbin is placed in initial position as indicated in Fig. 3, engage the slabbed-off portions of the bobbin and direct it in proper rotative position into engagement with the fulcrum 11. The guides 20 in the present instance of the invention extend from the wings 22 forwardly, one at each side of the strip 12 and are preferably connected as at 23, Figs. 1 and 2, that they may be held in operative relation.

In order that the bobbin-holding jaws and the guides 20 may be properly supported at their lower portions, there may be provided 65 a plate 24 underlying the portion 15 of the

strip 12 and having its side portions 25 extending beneath the lower edge of the bobbin-holding jaws and guides 20, the construction being such that the parts will be maintained in their operative relation, substantially as indicated in Figs. 1 and 2. 70

From the construction described as one practical form of the present invention, it will be noted that the shuttle may be interchangeably employed for a shuttle-changing 75 loom of the feeler type or a common loom, and while the construction described has been found to be a practically efficient form of the present invention, it will be understood that the parts may be variously 80 changed and that the fulcrum 11 may, if desired, be detachably connected to the shuttle, substantially as indicated in Fig. 2; and it will be further obvious that so far as the fulcrum is concerned, it may be variously 85 connected to the shuttle, the essential in this respect being that it shall act as a center or fulcrum point about which the bobbin may be turned into and out of operative relation 90 with the bobbin-holding jaws. 90

While the shuttle and bobbin as above described are well adapted for filling replenishing looms of the shuttle changing type employing a feeler motion, and are adapted for interchangeable use in such looms and 95 the common loom, it is to be understood that the present invention is not restricted to such use, as it may be employed in other relations and in any loom where the filling carrier or bobbin is to be placed in or taken 100 from the shuttle by hand.

What is claimed is:

1. A shuttle having bobbin-holding jaws for holding a bobbin in operative position therein, and a lug carried by the shuttle 105 constructed and arranged to engage and support the base end of a bobbin as a fulcrum as the bobbin is turned about the lug into holding relation with the jaws.

2. A shuttle having bobbin-holding jaws, 110 and a lug or projection secured to the shuttle between the jaws and adapted to engage and support the base portion of a bobbin as it is turned about said lug or projection as a fulcrum into operative position in the 115 shuttle.

3. A shuttle having bobbin-holding jaws, a lug carried by the shuttle to support the base portion of a bobbin as a fulcrum while 120 the bobbin is being turned into bobbin-holding relation with the jaws, and means for preventing longitudinal movement of the bobbin while it is being turned about said lug as a fulcrum.

4. In a shuttle, the combination of bobbin-holding jaws, a bobbin having a recessed base portion and holding rings or projections, a lug secured to the shuttle between the jaws to engage the recess in the base of the bobbin that the bobbin may be turned 125 130

about said lug as a fulcrum and forced between the holding jaws.

5. A shuttle provided with bobbin-holding jaws having transverse bobbin-holding grooves, a fixed lug or projection secured to the shuttle between planes passing longitudinally of said jaws and a bobbin having a base portion provided with a recess to engage said fixed lug when the bobbin is inclined to the shuttle that the bobbin may be turned about said lug into position between the bobbin-holding jaws.

6. A shuttle having bobbin-holding jaws, a fulcrum lug secured to the shuttle, a bobbin having a recess in its base portion to engage said lug when the bobbin is positioned inclined to the shuttle preparatory to being turned into operative position, and means to prevent axial rotation of the bobbin as it is turned about said lug as a fulcrum.

7. A shuttle having bobbin-holding jaws provided with transversely extending notches, a bobbin having projections engaging said notches when the bobbin is in operative position in the shuttle, and a lug carried by the shuttle and adapted to be engaged by the bobbin when the latter is initially positioned inclined relative to the shuttle preparatory to being turned into the shuttle, said jaws having inclined portions to engage the projections on the bobbin when the latter is initially positioned and acting to prevent longitudinal movement of the bobbin as it is forced into the shuttle about the lug as a fulcrum.

8. A shuttle provided with bobbin-holding jaws, a lug or projection secured to the shuttle between planes passing longitudinally of said jaws adapted to be engaged by a bobbin and constituting a fulcrum about which the bobbin is turned into holding relation with said jaws, and side guides hav-

ing upwardly extending wing portions adapted to engage and direct the bobbin in a predetermined rotative position as it is turned about said fulcrum.

9. A shuttle having bobbin-holding jaws, a fulcrum lug or projection having its axis inclined upwardly between said jaws and adapted to be engaged by a bobbin and forming a fulcrum about which the bobbin is turned into holding relation with said jaws.

10. A shuttle having bobbin-holding jaws, a lug or projection having its axis inclined upwardly between said jaws and forming a fulcrum at the base of the bobbin and about which the bobbin is turned into holding relation with said jaws, and means for preventing rotative movement of the bobbin as it is turned into operative position in the shuttle.

11. A shuttle having bobbin-holding jaws, a strip having an inclined portion between the jaws, a lug projecting from said inclined portion for engagement by a bobbin and serving as a fulcrum for the bobbin as it is turned into operative position in the shuttle.

12. A shuttle having bobbin-holding jaws, a bobbin provided with projections or rings for engaging said holding jaws and having an opening or recess for the entrance of a feeler, a lug or projection secured to the shuttle between planes passing longitudinally of the jaws and adapted to be engaged by the bobbin and serve as a fulcrum as the bobbin is turned into operative position in the shuttle, and means on the shuttle and bobbin adapted to engage and prevent rotary movement of the bobbin as it is turned about said fulcrum.

In testimony whereof I have signed my name to this specification.

UBALD HEBERT.
